DRIVING MECHANISM FOR TREMOLOS

Conrad P. Krueger, Hopkins, Minn., assignor to
Patent Management, Incorporated, Minneapolis, Minn., a corporation of Minnesota

Application April 14, 1948, Serial No. 20,932

2 Claims. (Cl. 74—111)

1

My invention relates to tremolos for musical instruments and particularly to musical instruments having sound generators each driven by a mechanically rotating element such as a shaft or the like operating at a substantially uniform rate of speed.

An object of the invention resides in providing a tremolo capable of producing variations in tone frequency as distinguished from variations in tone intensity.

An object of the invention resides in providing a tremolo embodying a driven element driven by the driving element and a flexible driving connection between said driving and driven elements.

Another object of the invention resides in providing a tremolo in which the driven element is periodically retarded to produce the tremolo effect and during which time the relative movement between the driving element and driven element is effected through the flexible driving connection.

A still further object of the invention resides in providing a mechanical brake mechanism for periodically retarding the driven element.

An object of the invention resides in providing spring means acting between the driving element and driven element in a tangential direction and accommodating relative rotational movement therebetween.

A still further object of the invention resides in constructing the driving element and driven element with juxtaposed concentrically revolvable plates, and in providing circumferentially spaced spring anchors on one plate with intervening openings therein and in further providing spring anchors on the other plate extending through said openings, together with springs, each anchored at one end to one of said first named spring anchors and at its other end to one of the other spring anchors.

In the drawings:

Fig. 1 is a side elevational view of a portion of a musical instrument illustrating an embodiment of my invention applied thereto and showing parts of the invention in section.

Fig. 2 is a cross sectional view taken on line 2—2 of Fig. 1.

Fig. 3 is a view similar to Fig. 2 illustrating a portion of the structure disclosed therein and showing some of the parts in altered position.

Fig. 4 is a fragmentary sectional view taken on line 4—4 of Fig. 3.

For the purpose of illustrating my invention I have shown in the drawings a portion of a

2

musical instrument 10. Since the invention does not concern itself with the construction of the musical instrument itself, only so much of the instrument as concerns itself with the tremolo has been shown. This instrument comprises a frame 11 which carries a number of tone generators one of which is indicated at 12. The tone generators are operated by means of a driven shaft 13 which is driven by a driving shaft 14 connected to an electric motor 15. These parts will now be described in detail.

The frame 10 comprises a number of elongated rods 16 on which are mounted a plurality of frame members 17a, 17b, etc., there being one such frame member for each tone generator. The frame 10 in addition, includes another frame member 18 which constitutes an end frame member for said frame and which is also mounted on the rods 16. Sleeves 19 encircle the rods 16 and are disposed between the frame members 17a, 17b etc., and 18 and nuts 21 screwed upon the ends of the said rods clamp the parts securely together. Issuing outwardly from the frame 10 is a shelf 22 which is attached to the frame member 17a and to the end frame member 18 by means of angles 23 and 24 riveted to each frame member and said shelf. This shelf is braced relative to the frame 10 by means of a brace 25 which is secured to said shelf and the frame member 17a by bolts 26.

30 The motor 15 may be of conventional construction and is preferably of the synchronous type. This motor is secured to the shelf 22 by means of bolts 27 which pass through feet 28 on said motor and are threaded into the shelf 22. The 35 driving shaft 14 is the rotor shaft of the motor 15 and is rotatably mounted in the usual bearings of the motor. This shaft extends through the end frame member 18 and is operatively connected to the driven shaft 13 as will be subsequently described.

The driven shaft 13 extends through all of the frame members 17a, 17b etc., and is rotatably mounted in a number of bearings, one of which is indicated at 29 and which are attached to certain of the frame members 17a, 17b, etc. The shaft 13 in the form of the invention illustrated, is disposed in axial alignment with the shaft 14 and the end of the same extends up to and in close proximity to the end of the shaft 14.

50 The tone generator 12 consists of a magnet 31 having a core 32 and a winding 33 mounted on said core. The core 32 is attached to the frame member 17b by means of a screw 34 which is threaded into the core 32. The other end 35 of the core 32 forms a pole which cooperates with

a tone wheel 36. The tone wheel 36 may be a serrated ring of ferrous metal or any other construction having a number of spaced teeth or sections adapted to cooperate with the pole 35 upon rotation of said wheel to vary the reluctance of the magnetic circuit containing the core 32 and to correspondingly vary the current flowing through the winding 33. The tone wheel 36 is mounted upon a shaft 37 which is rotatably supported in a bearing 38. Bearing 38 is attached to bracket 39 which is secured to the frame member 17a by means of an angle 41 similar to the angles 23 and 24. The lower end of the shaft 37 has secured to it a driven wheel 42 which has mounted on it a rubber tire 43. This contacts a disc 44 attached to a hub 45. The hub 45 is mounted on shaft 13 and is held in position by means of a set screw 46. The wheel 42 can be adjusted on the shaft 37 to vary the speed ratio between said wheel and the disc 44 whereby the tone wheel 36 may be driven at any suitable speed within certain limits and tones of the desired frequencies can be produced by the various generators. The windings 33 of the various tone generators are connected through suitable switches operated by the keys of a keyboard of the musical instrument to suitable electrical circuits including an amplifier and a loud speaker whereby the electrical impulses set up in the magnetic circuit including the core 32, are converted into audible sounds.

The invention proper includes a plate 48 which has issuing from it a hub 49. Hub 49 is secured to the shaft 13 by means of a set screw 51. The plate 48 is disposed at the end of the shaft 13 and lies between the two frame members 17a and 18. The outermost portion of the plate 48 has a flange 52 extending therefrom and which forms a brake drum. Within the drum 52 is disposed a plate 53 similar to the plate 48 and slightly spaced therefrom. This plate has a hub 57 issuing therefrom and which is mounted on the end of the shaft 14. The plate 53 is secured to a shaft 14 by means of a set screw 55 threaded into hub 57. The plate 48 is formed with three circumferentially arranged openings 56 best shown in Fig. 2. On the plate 53 are three studs 57 which extend through the openings 56 and which form spring anchors. On the plate 48 and between the openings 56 are provided studs 58 which are similar to the studs 57 and which are arranged at the same distance from the axis at the shaft 13a and 14 as the studs 57. Between the studs 57 and 58 are located tension coil springs 59 which have their ends 61 hooked over said studs. These springs are normally slightly tensioned and serve to connect the two shafts 14 and 13 together. By means of this construction a driving connection between the two shafts is afforded including driving element 53 and a driven element 42 permitting of relative rotation or movement between the elements.

Cooperating with the brake drum 52 is a brake shoe 60 which is mounted on and attached to a lever 62. Lever 62 is angular in form having a vertical leg 91 and a horizontal leg 92. Lever 62 is pivoted to the end frame 17 by means of a stud 63 which extends outwardly therefrom and which passes through the leg 91. A nut 64 screwed on the end of said stud holds the same attached to said frame member. The lever 62 is urged downwardly as viewed in Figs. 2 and 3 by means of a compression coil spring 65 which engages the leg 92 and is attached to a screw

66. This screw is threaded in a bracket 67 attached to the frame member 18. A lock nut 68 on said screw holds the same in position. The leg 92 of the lever 62 at the forward end thereof is formed with a hole 69 through which a Bowden wire 71 extends. This wire has a collar 72 secured to the end of it and which is adapted to engage the under surface of the leg 92 and to raise said lever in opposition to the spring 65 to disengage the shoe 60 from the brake drum 52.

For operating the tremolo, a friction wheel 76 is employed which is mounted on a stub shaft 75 which extends outwardly from the end frame member 18. The friction wheel 76 is provided with a hub 93 through which the shaft 74 extends and a washer 94 on the end of said shaft holds the wheel in place. On the wheel 76 is a tire 77 which is adapted to engage a friction roller 79 secured to the shaft 14. By means of this construction the wheel 76 is driven from the shaft 14 at a suitable speed. Mounted on the wheel 76 is a cam 73 in the form of an annulus which is eccentrically disposed relative to the shaft 74. Screws 95 pass through the cam 73, and through spacers 96 and are threaded into the wheel 76 to hold the cam 73 mounted thereon to rotate with it. Cooperating with the cam 73 is a cam follower 83 which is mounted on an arm 84. This arm is secured to the leg 92 of arm 62 and its position with reference to it may be varied by means of an adjusting screw 85 which is screwed into a bar 86 attached to the leg 92 of the lever 62 and which is held in position by means of a lock nut 87.

The operation of the invention is as follows: When the motor 15 is energized, shaft 14 drives the shaft 13 through the springs 59 connecting the plates 48 and 53 together. Normally with the lever 62 in raised position as shown in Fig. 2, the shoe 60 is free from the brake drum 52 and the shaft 13 is driven at a constant uniform speed. If the control wire 71 is lowered to the position shown in Fig. 3, the collar 72 is moved away from lever 62 and spring 65 urges the said lever downwardly and the brake shoe 60 into engagement with drum 52. This places a drag upon the said drum which causes the relative movement between the driving element 53 and the driven element 42. This causes the springs 59 to be tensioned until the force produced by the friction of the brake equals the force required to stretch the springs. The parts now rotate in relatively altered rotational relation. At the same time, the cam follower 83 is riding upon the cam 73. When the said follower is raised sufficiently by the cam, the shoe 60 becomes disengaged from the drum 52 and the springs 59 bring the driven and driving elements back into normal relationship. As the shaft 14 rotates, cam 73 causes the driven element to be alternately retarded and accelerated and the tone generators to be alternately slowed down and speeded up. This produces the desired tremolo effect. By adjusting the tension on the spring 65 through screw 66, and by adjusting the screw 85, different tremolo effects can be produced.

The advantages of the invention are manifest. The device is extremely simple in construction and positive in action. The tremolo effect can be adjusted to produce an appreciable periodic variation in frequency or only a slight variation as desired. The device is entirely mechanical and can be readily installed in existing machines utilizing revoluble tone generator elements.

Changes in the specific form of my invention, as herein described, may be made within the scope of what is claimed without departing from the spirit of my invention.

Having described my invention, what I claim as new and desire to protect by Letters Patent is:

1. In a tremolo a rotatable driving element and a rotatable driven element, a spring positively connected at one end to said driving element and positively connected at its other end to said driven element and constituting a flexible coupling continuously acting between said driving element and said driven element and affording limited relative rotational movement therebetween, a brake drum rotatable with said driven element, a brake shoe for cooperation therewith, guide means for guiding said brake shoe for movement toward and from said drum and restraining circumferential movement thereof relative to said drum, a rotatable cam driven by said driving element, a cam follower engageable with said cam and resilient means acting between said cam follower and brake shoe, and resilient means urging said brake shoe toward said drum, said cam operating in opposition to both of said resilient means.

2. In a tremolo a rotatable driving element and a rotatable driven element, a spring positively connected at one end of said driving element and positively connected at its other end to said driven element and constituting a flexible coupling continuously acting between said driving element and said driven element and affording

limited relative rotational movement therebetween, a brake drum rotatable with said driven element, a brake shoe for cooperation therewith, guide means for guiding said brake shoe for movement toward and from said drum and restraining circumferential movement thereof relative to said drum, a rotatable cam driven by said driving element, an arm mounted on said guide means and movable relative to said guide means in a direction toward and from the axis of said brake drum, a cam follower carried by said arm and engageable with said cam, adjusting means for adjusting the position of said arm and brake shoe and resilient means for urging said brake shoe toward said drum, said cam operating in opposition to said resilient means.

CONRAD P. KRUEGER.
